INVENTOR.
W. S. Johnson,

BY

BY
Geo. P. Kimmel
ATTORNEY.

UNITED STATES PATENT OFFICE.

WILLIAM S. JOHNSON, OF ELECTRA, TEXAS.

DRILL.

Application filed February 20, 1923. Serial No. 620,250.

To all whom it may concern:

Be it known that I, WILLIAM S. JOHNSON, a citizen of the United States, residing at Electra, in the county of Wichita and State 5 of Texas, have invented certain new and useful Improvements in Drills, of which the following is a specification.

This invention relates to drills, more particularly to the manner of connecting the 10 bit with the collar, chuck or collet of the drill, designed primarily for use in connection with the drilling of oil wells, yet it is to be understood that a drill in accordance with this invention can be employed for any 15 purpose wherein it is found applicable, and the invention has for its object to provide in a manner as hereinafter set forth, means to so set up a detachable connection between the bit and collar, chuck or collet of the drill 20 whereby the employment of screw threads for such purpose is dispensed with, under such conditions providing what may be termed a threadless socket bit.

A further object of the invention is to 25 provide in a manner as hereinafter set forth, a drill including means to provide for quickly connecting and disconnecting the drill bit to and from the collar, chuck or collet of the drill without the providing of the bit with 30 threads for engagement with the collar, chuck or collet to secure the bit in position.

Further objects of the invention are to 35 provide a drill for the purpose set forth which is simple in its construction and arrangement, strong, durable, efficient and convenient in its use, readily assembled and comparatively inexpensive.

With the foregoing and other objects in view, the invention consists of the novel construction, combination and arrangement of 40 parts as hereinafter more specifically described and illustrated in the accompanying drawings, wherein is shown an embodiment of the invention, but it is to be understood 45 that changes, variations and modifications can be resorted to which come within the scope of the claims hereunto appended.

In the drawings wherein like reference 50 characters denote corresponding parts throughout the several views:—

Figure 1 is a sectional elevation, broken away, of a drill in accordance with this invention.

Figure 2 is a section on line 2—2, Figure 55 1.

Referring to the drawings in detail, a drill

in accordance with this invention includes a chuck, collet or collar, referred to hereafter as a collar, and further includes a bit element which is detachably connected with the 60 collar without the employment of screw threads, and the collar is adapted to be secured to a casing section or other means for rotating the drill.

The collar includes an upper portion 1 65 and a lower portion 2, the former being of materially less thickness than the latter and provided with internal threads 3. The lower part of the inner face of the lower portion 2 of the collar is beveled to form a conoidal-shaped socket 4, and the bottom edge of the lower portion 2 of the collar is formed with an annular groove 5.

The beveled part of the lower portion 2 of the collar, is provided with a plurality of 75 transversely extending openings and the number of these openings can be as many as desired, as shown four in number, and arranged equi-distantly apart and which are indicated at 6, and the wall of each of the openings 6 is threaded. The inner face of the beveled part of the lower portion 2 of the collar is formed with a plurality of sockets as indicated at 7 and with which register the inner ends of the openings 6. 80 There is a socket 7 associated with each of the openings 6. The outer periphery of the beveled part of the lower portion 2 of the collar is provided with a plurality of pockets 8 and with the inner portion of the wall of 85 each pocket 8 beveled as at 9. The pockets 8 register with the openings 6 and the arrangement is such that the number of pockets correspond with the number of openings. 90

That part of the lower portion 2 of the 95 collar, above the socket 4, provides a water channel 10, which opens into a water space 11 formed by the upper portion 1 of the collar. Extended into the upper portion 1 of the collar, as well as having threaded engagement therewith, is a pipe section 12 or 100 other element employed for operating the drill.

The bit element comprises a body portion 13 of greater diameter than the collar and 105 which is formed with a cutting end 14 of inverted V-shape. Formed integral with the top of the body portion 13 is a conoidal-shaped tang 15 having its base of less diameter than the diameter of the body portion 110 13 whereby the latter at its upper end is formed with an annular ledge 16, and

formed integral with the ledge 16, is a vertically disposed annular flange 17, which extends into the groove 5.

The tang 15, between its transverse center

5 and its upper end, is provided with a continuous annular groove 18 in its periphery and said groove has a flat bottom wall 19 and an upwardly extending and outwardly inclined upper wall 20.

10 The bit element is provided with an axial bore 13' which extends through the body portion 13 and tang 15 and opens into the water passage 10 when the bit element is secured to the collar.

15 When the bit element is arranged in position to be connected with the collar, the groove 18 opposes the sockets 7 and the tang 15 is detachably connected with the collar, through the medium of a plurality of transversely extending clamping elements each consisting of a threaded shank 21 having its inner end provided with a clamping head 22 and its outer end with a grooved beveled head 23.

20 25 A clamping element is extended through each of the openings 6 and the shank of such element has threaded engagement with the threaded wall of the opening 6. The clamping heads 22 bind against the upper wall 20 of the groove and that face of each of the heads 22, which binds against the wall 20, is beveled as at 24. The heads 23 are adapted to be seated against the beveled wall portions of the pockets 8 and the 30 35 grooves in the heads 23 provide means for the convenient adjusting of the clamping elements by a suitable tool.

As illustrated, the collar 2 is provided with four openings 6 and associated with each opening is a clamping element, but if desired two openings 6 may be employed and a corresponding number of clamping elements.

40 45 The manner of setting up the bit element with respect to the collar provides for quickly connecting, as well as disconnecting the bit element to and from the collar and the connection between the bit element and collar is set up without the employment of threads on the tang or on the collar, under such 50 55 conditions the device provides what may be termed a threadless socket bit.

The body portion 13 is illustrated as provided with an annular flange 16, but in lieu thereof independent lugs can be employed, 55 two or more, and engage in sockets formed in the lower edge of the collar and when the sockets are employed the annular groove 5 is dispensed with.

60 65 From the foregoing description taken in connection with the accompanying drawings, a drill is set up whereby the bit element is connected with the collar without the employment of interengaging threads and although the preferred embodiment of the invention is as shown and described, yet it is

to be understood that changes in the details of construction can be had without departing from the spirit of the invention as claimed.

What I claim is:—

70 1. A drill comprising a collar having a conoidal-shaped socket at its lower end, a bit element provided with a tang extended into said socket and formed with a peripheral groove having one of the walls thereof outwardly inclined, and transversely extending clamping elements threadingly engaging with said collar and provided with beveled clamping heads binding against said wall for detachably connecting the bit element 80 with the collar.

75 2. A drill comprising a collar having a conoidal-shaped socket at its lower end, a bit element provided with a tang extended into said socket and formed with a peripheral groove having one of the walls thereof outwardly inclined, and transversely extending clamping elements threadingly engaging with said collar and provided with beveled clamping heads binding against said wall 85 for detachably connecting the bit element with the collar, said collar having its lower edge grooved, and said bit element provided with a flange extending in said groove.

90 3. A drill comprising a collar having 95 means to provide a conoidal-shaped socket at its lower end, the wall of said socket provided with a plurality of sockets disposed at right angles with respect to said conoidal-shaped socket, said collar further having its periphery provided with pockets in alignment with the sockets formed in the walls of said conoidal-shaped socket, said collar further provided with transverse openings leading from said pockets, a bit element with a tang extended into said 100 105 conoidal-shaped socket and having its periphery provided with a continuous groove with one wall thereof outwardly inclined, and clamping elements including threaded shanks engaging with the walls of said openings and having their inner ends provided with clamping heads formed with beveled faces binding against said inclined walls thereby connecting said bit element with said 110 115 collar, said shanks extending through the sockets disposed at right angles with respect to said conoidal-shaped socket, and said shanks having their outer ends provided with heads seating in said pockets.

120 4. A drill comprising a collar having means to provide a conoidal-shaped socket at its lower end, the wall of said socket provided with a plurality of sockets disposed at right angles with respect to said 125 conoidal-shaped socket, said collar further having its periphery provided with pockets in alignment with the sockets formed in the walls of said conoidal-shaped socket, said collar further provided with transverse open-

ings leading from said pockets, a bit element with a tang extended into said conoidal-shaped socket and having its periphery provided with a continuous groove with one wall thereof outwardly inclined, and clamping elements including threaded shanks engaging with the walls of said openings and having their inner ends provided with clamping heads formed with beveled faces 5 binding against said inclined walls thereby connecting said bit element with said collar, said shanks extending through the sockets disposed at right angles with respect to said

conoidal-shaped socket, and said shanks having their outer ends provided with heads 15 seating in said pockets, said bit element provided with an axial bore opening into said collar and said collar provided with means for connecting a bit operating element therewith, said collar having its lower edge 20 grooved, and said bit element provided with a flange extending into the grooved end of the collar.

In testimony whereof, I affix my signature hereto.

WILLIAM S. JOHNSON.
